UNITED STATES PATENT OFFICE.

MEYER BAYUK, OF GLENSIDE, PENNSYLVANIA.

DISPLAY-COVER AND GUARD FOR BOXES.

1,105,240.

Specification of Letters Patent. Patented July 28, 1914.

Application filed July 15, 1913. Serial No. 779,097.

To all whom it may concern:

Be it known that I, MEYER BAYUK, a citizen of the United States, residing at Glen-side, in the county of Montgomery, State of Pennsylvania, have invented a new and useful Display-Cover and Guard for Boxes, of which the following is a specification.

My invention consists of a cover adapted to display the contents of a box and guard the same from dust, dirt, and improper handling for sanitary purposes, the same being adapted to be connected with the lid proper of the box so that said lid may be held open, thus exhibiting the trade-mark, brand, or other characteristics of the contents of the box, and said cover may admit access to said contents.

The invention is satisfactorily illustrated in the accompanying drawing, but the important instrumentalities thereof may be varied, and so it is to be understood that the invention is not limited to the specific arrangement and organization shown and described.

Figures 1 and 2 represent perspective views of covers for boxes embodying my invention, they being in different positions in the two figures. Fig. 3 represents a perspective view of a cover taken from the rear of Fig. 1. Fig. 4 represents a top or plan view of the cover.

Similar numerals of reference indicate corresponding parts in the figures.

Referring to the drawings: 1 designates a box, and 2 designates the lid thereof, the latter being attached to the former by a flexible hinge as well known, said box in the present case being of the order adapted to contain cigars, to the use of which goods, however, I do not limit myself.

3 designates a supplemental cover formed of a plate 4 of transparent material, preferably glass, and a frame or rim 5 therefor, preferably metal, said cover being adapted to be placed over the contents of the box to protect the same from dust, dirt, and improper handling, which permits said contents to be displaced, viewed and inspected without necessarily raising or opening said cover, but as is evident, access may be had to said contents by raising the said cover.

To the rear portion of the frame of the cover 3 at or about the sides thereof are the rigidly secured inturned ears 6, comparatively U-shaped turned laterally, they being open through in vertical direction, and sep-

arated on their inner ends and having their bends on their outer ends so that the ears can be slipped down over the side edges of the lid 2 of the box, said lid being raised, as in Fig. 1, and consequently open. When said ears are in operative position, which is adjacent to the hinge of said lid they place the cover 3 on the top of the box over the contents thereof, and connect said cover with the lid of the box. In order to strengthen the connection of the ears with the frame of the cover, I employ the bar or plate 7 which is continuous of the ears and rigidly secured to said frame, said strip or bar also extending along the inner face of said lid near the hinged edge thereof, thus assisting to support said lid when raised and serving also to brace said lid about its hinged edge in the longitudinal direction thereof. It will now be seen that the cover 3 has for its hinge the hinge of the lid of the box consequently the cover when in normal position may be grasped and then raised in front to afford access to the goods, it turning with the lid on the hinge or axis of the latter, said lid moving rearwardly to a greater extent so as not to interfere with the ascent or opening of the cover, as illustrated in Fig. 2. Again, when the cover is in normal position, the lid 2 of the box may be grasped and turned backwardly when the cover 3 follows the motions thereof and rises from the box uncovering the contents thereof and permitting access thereto. By these means the cover may be operated to be raised from the box from in front or at the rear of the latter, and as evident, said cover with its ears may be removed and applied to another box and lid.

Having thus described my invention what I claim as new and desire to secure by Letters Patent is:

1. A cover for a box supplemental to the lid thereof provided with laterally turned ears rigid thereon for connection with the sides of said lid and rendering said cover movable with said lid on the hinge of the latter, said ears being connected by a reinforcing plate on said cover.

2. A supplemental cover for a box composed of transparent material, and ears on the rear thereof, said ears being adapted to engage the sides of the lid of the box thereby connecting said cover with said lid and constituting the hinge of the lid as that of said cover and a longitudinally extending

rim on the rear of the frame of the cover the same having said ears connected therewith.

3. A supplemental cover for a box composed of transparent material, a longitudinally extending rim on the rear of the frame of said cover, and inturned ears connected with said rim, said ears being adapted to

be fitted on the sides of the lid of the box thereby connecting said cover with said lid, the hinge of the latter being common to said cover.

MEYER BAYUK.
